UNITED STATES PATENT OFFICE.

WALTER J. GORMAN, OF JERSEY CITY, NEW JERSEY.

BURIAL VAUL

Application filed March 19, 1927. Serial No. 178,664.

This invention relates to burial vaults, and particularly to devices of this class adapted for use in mausoleums; and the object of the invention is to provide an improved vault

5 construction whereby a number of vaults may be mounted one upon the other to provide a simple and yet compact storage of the vaults in a mausoleum; a further object being to provide means for utilizing a vault 10 construction wherein the mounting of one vault upon the other, the top of a lowermost vault may constitute the bottom of the next adjacent vault, thereby effecting a saving in material; a further object being to provide means for reinforcing the walls of the vault and providing a vent tube therein for the discharge of the gases; a still further object being to provide simple and effective means for coupling and sealing the doors of 15 20 the vaults; and with these and other objects in view, the invention consists in a vault of the class and for the purpose specified, which is simple in construction, efficient in use, and which is constructed as hereinafter described 25 and claimed.

The invention is fully disclosed in the following specification, of which the accompanying drawing forms a part, in which the separate parts of my improvement are designated by suitable reference characters in each of the views, and in which:

Fig. 1 is a side and sectional view of one form of vault which I employ.

Fig. 2 is a face view of the vault shown in Fig. 1, on a reduced scale and with part of the construction broken away.

Fig. 3 is a sectional, detail view of a part of the construction shown in Fig. 1 of the drawing.

40 Fig. 4 is a perspective and sectional view of a modified form of construction which I employ; and,

Fig. 5 is a perspective view of an open end vault made according to my invention.

45 In Figs. 1 and 2 of the drawing, I have shown a vault composed of cement, concrete or other material. In the construction shown, the vault comprises a back wall 10, top wall 11, bottom wall 12 and end walls 13. 50 The front side of the vault is open and provided with a groove 14 on the inner face of the walls of the vault at the open side. A strip 15 of metal is imbedded in the walls of the vault adjacent the groove 14, and has 55 at intervals, inwardly pressed portions 16 whereby a sealing compound 17 will operate

to seal the door 18 employed for closing the open end of the vault. The strips 15 also serve to give strength to the open side of the vault.

60 The vault is reinforced by a body of open-work material 19 imbedded in the back, top, bottom and end walls. If desired, this material may be anchored to the strip 15 as well as to bolts 20 employed for mounting lugs 65 21 at the open side of the vault for engaging the door 18 to hold the same in closed position, and further to permit of the removal of the door at will.

I also preferably imbed in the back wall 70 10 of the vault, a trap 22 which opens into the chamber 23 of the vault and out through said back wall to allow for the escapement of gases. I also imbed in the bottom wall 12 of the vault, adjacent the ends thereof, 75 two strips 24 having anti-friction rollers 25 whereby the casket 26 indicated in dot and dash lines, Figs. 1 and 2, may be easily rolled into the chamber 23 of the vault. The door 18 is provided with a number of ring-like handles 27 anchored to the concrete of the door or the reinforcing material 28 employed in the door construction.

80 In the use of the vault shown in Figs. 1 and 2 of the drawing, and especially in stacking the same, the lowermost vault is mounted upon back and end strips 29 to space the same from a floor or other support, and the vault placed upon the lowermost vault is spaced therefrom by similar back and end strips 30, and thus the next vault is placed on strips 31 to the desired height. A chamber 32 is 85 preferably arranged at the backs of the vaults to allow for the escape of the gases which may be discharged from the traps 22. 90 95

In Fig. 4 of the drawing, I have shown a slight modification wherein the lowermost vault 33 of a stack of vaults is identical with the vault shown in Figs. 1 and 2, with the exception that the top of the back and side portions of the vault, is provided with sockets 34 to receive pins 35 on the next adjacent vault 36. The vault 36 differs from the vault 33 or the vaults shown in Figs. 1 and 2, simply in that the bottom wall 12 is 100 not employed. The bottom of the vault 36 is formed by the top wall 11 of the vault 33, and the vault 33 is further modified in that strips 37 similar to the strips 24 are mounted upon the outer face of the top wall 11, and 105 in like manner, similar strips 37 are mounted upon the outer faces of the top wall of the 110

vault 36. Another vault 38 is mounted upon the vault 36, and if this vault be the uppermost vault employed, the strips 37 will be eliminated. Otherwise, the vault would be identical with the vault 36. Aside from the foregoing, the structure of the multiple vault shown in Fig. 4 of the drawing will be the same as that shown in Figs. 1 and 2 of the drawing, except further that the lower grooves of the vaults 36 and 38 are omitted, and the lugs 21 are double ended to engage the covers 18 of the vaults 33-36 and 36-38.

In Fig. 5 of the drawing, I have shown another modification, wherein the vault 39 is open at one end only, and said open end is grooved as seen at 40 to correspond with the grooves 14 to receive a door 41 held in place by lugs 42 similar to the lugs 21. In this form of construction, an anti-friction roller strip 43 is mounted centrally and longitudinally of the inner face of the bottom of the vault. The type of vault shown in Fig. 5 may be found practical for use in certain types of mausoleums, and where the exposed end stacking of the vaults is desirable.

It will be understood that these vaults may be stacked one upon another and side by side as in the construction shown in Figs. 1 to 4 inclusive, and the vent tube will be located at the back wall as in the construction shown in said other figures. Suitable means may be provided for coupling and spacing the vaults in stacking the same, as will be apparent.

It will be understood that while I have shown certain details of construction for carrying my invention into effect, and have referred to a specific use of my improved vaults, that I am not necessarily limited to the construction herein shown and described, and various changes therein and modifications thereof may be made within the scope of the appended claims without departing from the spirit of my invention or sacrificing its advantages.

Having fully described my invention, what I claim as new and desire to secure by Letters Patent, is:

1. A vault, L-shaped in cross section comprising back, top and end walls integrally connected, the bottom being adapted to fit the top of the next lower vault in a stack, and a door to close the front.

2. A vault, L-shaped in cross section com-

prising back, top and end walls integrally connected, the bottom being adapted to fit the top of the next lower vault in a stack, a door to close the front, and the bottom vault of a stack including top and bottom walls. 60

3. A vault, L-shaped in cross section comprising back, top and end walls integrally connected, the bottom being adapted to fit the top of the next lower vault in a stack, a door to close the front, and means imbedded 65 in the front edges of the vault, for retaining the door against displacement.

4. A vault, L-shaped in cross section comprising back, top and end walls integrally connected, the bottom being adapted to fit 70 the top of the next lower vault in a stack, a door to close the front, and anti-frictional devices arranged on one wall of the vault and exposed to the chamber within the vault to facilitate the placement of caskets 75 therein.

5. A vault, L-shaped in cross section comprising back, top and end walls integrally connected, the bottom being adapted to fit 80 the top of the next lower vault in a stack, a door to close the front, said vault being composed of reinforced concrete, and a trap imbedded in one wall thereof to permit the escapement of gases.

6. A vault construction of the class described comprising a plurality of independently formed vaults adapted to be mounted one upon the other, each of said vaults being L-shaped in cross section, comprising back, top and end walls integrally connected, the 85 bottom of one vault being adapted to fit the top of the next lower vault in a stack of vaults and a door to close the front of each vault.

7. A vault construction of the class described comprising a plurality of independently formed vaults adapted to be mounted one upon the other, each of said vaults being L-shaped in cross section, comprising back, top and end walls integrally connected, the 90 bottom of one vault being adapted to fit the top of the next lower vault in a stack of vaults and a door to close the front of each vault, and means imbedded in the front edges of the top wall of the vault for retaining the 100 doors against displacement.

In testimony that I claim the foregoing as my invention I have signed my name this 17th day of March, 1927.

WALTER J. GORMAN.
